UNITED STATES PATENT OFFICE.

GEORGE C. WRIGHT, OF EAST LANSING, MICHIGAN.

COMBINATION FUEL FEED AND GOVERNOR.

Application filed March 6, 1923. Serial No. 623,236.

To all whom it may concern:

Be it known that I, GEORGE C. WRIGHT, a citizen of the United States, residing at East Lansing, in the county of Ingham and 5 State of Michigan, have invented certain new and useful Improvements in Combination Fuel Feeds and Governors; and I do hereby declare the following to be a full, 10 clear, and exact description of the invention, such as will enable others skilled in the art to which it appertains to make and use the same.

The object of the invention is to provide an efficient fuel feeding and governing 15 mechanism for use in connection with motors of the internal combustion or explosion type which are subject to variations in speed or rate of operation for the purpose of regulating the speed through the control of the 20 fuel or the feed of the fuel to the cylinders, whether the fuel is fed directly thereto in liquid or sprayed form or through a carburetor; and with this object in view the invention consists in a construction, combination 25 and relation of parts of which a preferred embodiment is shown in the accompanying drawings, wherein:

Figure 1 is a view of an apparatus embodying the invention, in connection with 30 which is shown a pump of the gear type adapted for actuation by the crank shaft or other convenient portion of the motor.

Figures 2, 3 and 4 are respectively sectional views on the planes indicated by the 35 lines 2-2; 3-3 and 4-4 of Figure 1.

Figure 5 is a view principally in vertical section through a modified form, and

Figure 6 is a view principally in vertical section through a second modified form.

The casing 10 constitutes a reservoir for oil or other fuel to be fed either directly to the cylinders under the control for example of the needle valve 11 or its equivalent or to a carburetor as in the ordinary practice, the former of these methods being indicated merely for convenience in the drawing with the needle valve casing 12 discharging directly into a fuel cup 13 fitted in the head of the cylinder indicated at 14 under the control of a fuel inlet and air intake poppet valve 15, into the seat 16 of which the needle valve port 17 opens. Communication with the needle valve casing is made by a feed tube 18 and the needle valve 50 stem 19 is fitted with a coiled spring 20 bearing against a collar 21 and tending yielding

ingly to hold the needle valve unseated, the tension of the spring being under the control of a stop nut 22.

Fuel is supplied through the pipe 23 to 60 the reservoir 10, the fuel coming from any preferred source of supply, (not shown), and first entering a cylinder 24 arranged within the reservoir and containing a piston 25 which is exposed to the pressure of the 65 incoming fuel and yieldingly resists this pressure in accordance with the tension of a spring 26 coiled upon the stem 27 of the piston, which stem, passing slidably through a gland 28 in the head of the reservoir, has 70 connection by means of a collar 29 with one end of a rocking lever 30, fulcrumed at 31 and engaged at the extremity of its other arm with the collar 21 on the needle valve stem. The tension of the spring 26 is controlled by the gland 28 which is in the form of a thimble threaded in the head of the reservoir. Preferably the arm of the rocking lever carries an adjustable screw 32 of 75 which the extremity constitutes a tappet or contact point 33 for engagement by the end of the piston rod or stem 27 when elevated, the screw 32 being held in its adjusted position by the lock nut 34 and in order to cut off the supply of fuel to the motor at a point 80 close to the latter, so that the operation of the motor will cease as soon as the cut off has been operated, the rocking lever at or near the end adjacent to the piston rod or stem, as shown in the drawing, is provided 85 with a stop lever 35 having a cam 36 pivotally mounted as at 37 on the lever 30 and adapted to bear against any adjacent fixed object, such as the upper end of the adjusting sleeve or gland 28. The tilting of the 90 lever due to the operation of this cam in throwing the cut off lever to its adjusted position serves to move the needle valve in opposition to its actuating spring 20 into a seated or closed position.

The reservoir 10 is provided with an overflow 37 through which the fuel upon reaching the level thereof flows back to the source of supply or tank, and the oil which enters the cylinder 24 and to which through pressure upon the piston 25 and the rocking lever 30 serves to control the extent of opening of the needle valve and hence the quantity supply of fuel to the engine or motor, is deflected through a by-pass 38 to enter the 105 body of the reservoir 10, the by-pass having a vertical tubular portion fitted with a pres-

- sure control valve 39, manually operable, and adapted by the position thereof to offer greater or less obstacle to the escape of the fuel oil therefrom into the reservoir to increase or diminish the effect of the feed pressure upon the piston 25 and hence qualify or modify the effect of the fuel pressure upon the needle valve or the position of the latter with reference to its seat and hence the relative rapidity of feeding of the fuel to the cylinder through the feed pipe 18 which carries the fuel oil by gravity from the reservoir 10 to the needle valve port 17.
- 15 As a means of preventing the motor from racing, in event that the supply pressure should diminish in the cylinder either through the exhaust of the fuel in the supply tank or source or otherwise, tending to permit the depression of the piston 25 under the influence of the tension of the spring 26 and hence the movement of the rocking lever to open the needle valve to its fullest extent, the feed pipe 18 is provided in the reservoir 20 with an inlet valve seat 40, and a cut off valve 41 is arranged in operative relation with said seat and has its stem connected with the longer arm of the rocking lever as at 42, so that the depression of this arm of the lever serves to seat the valve 41 and hence cut off the supply of oil from the reservoir to the needle valve, upon the decrease or discontinuance of supply pressure to the reservoir.
- 25 The point of valve 11 is flattened as at 9 so that the valve can not completely close its seat which is important in preventing the engine from hunting on "no load" since otherwise the valve would periodically completely close and open too wide, thus, respectively cutting off the fuel and racing. It is obvious that this incomplete closing of valve 11 to the desired degree may be effected in any other way, for instance by providing a groove in the point of the valve or its seat or by a stop on the valve or its seat to prevent complete closing of the valve.
- 30 Thus by the regulation of the tension of the spring 26 and the adjustment of the contact 33 and the adjustment of the collar 21 on the needle valve, the relative amount of feed by the needle valve to the pressure may be regulated to a fine degree with the assurance that increase or variation tending to increase supply pressure will be compensated for through the connecting rocking lever 30 by a corresponding closing movement of the needle valve to insure a uniform rate of movement of the motor, the fuel in the reservoir not being affected by the pressure but being conveyed to the cylinder by gravity; and in addition the amount of effect of the supply pressure upon the piston and hence upon the position of the needle valve is further controlled by the pressure

control valve 39 which regulates the opening of the by-pass through which the supply pressure is admitted to the reservoir, with the result that practical uniformity of speed or rate of movement of the motor is assured, and when it is desired to stop the motor or through the diminution of supply pressure the tendency of the piston 25 is to widely open the needle valve, the supply to the cylinder is cut off either by seating the needle valve through the operation of the cut off lever 36 or through the seating of the cut off valve 41 at the inlet end of the feed tube 18, so that there is no tendency for the motor to run for any length of time after either of the cut off means has been actuated.

In the modified construction shown in Figure 5 the fuel under pressure is admitted through the supply pipe 23^a and enters an expansible or bellows shaped preferably metallic receptacle 25^a constituting the equivalent of the piston 25 of the form previously described in that it is a pressure controlled element movable proportionately to the pressure under which the fuel is supplied under the control of a pressure valve 39^a which regulates the inlet of the fuel from the pressure chamber represented in this instance by the interior of the diaphragm 25^a and in the previously described form by the cylinder 24, to the interior of the reservoir 10^a through a bypass 25^b, said reservoir having the overflow 37^a adapted to lead as previously described to the tank or source of supply.

The body portion of the reservoir 10^a is carried by the movable member of the pressure controlled element 25^a and is provided with a feed passage 18^a leading to the casing 12^a of the needle valve 11^a, the needle valve in this case being tubular to provide a passage 11^b through which the fuel passes to the casing 12^a and the spring 20^a being employed to resist the seating movement of the needle valve as in the construction previously described, the needle valve stem being attached in the modified form directly to the casing of the reservoir and being carried thereby so that the extension of the yielding member 25^a of the pressure controlled means, due to an increase in pressure of the supply tends to close or cause a seating movement of the needle valve to close the needle valve port 17^a which as previously described is controlled in turn by the poppet valve 15^a having the usual means adapting it to yield to the suction strokes of the engine of which the cylinder is accessible through the fuel cup 13^a, as illustrated in the drawing, or a carburetor as frequently employed in this connection. The point of valve 11^a is shaped like that of valve 11 for the same purpose. The fuel feed and governor mechanism herein described is designed for use in connection with a variety of fuel oils of dif-

ferent degrees of viscosity, and to adapt it to these uses it is preferable to employ in connection therewith a force feed means consisting of a pump inserted in the supply line 5 between the tank and the reservoir to which admission is controlled as above described by the pressure actuated means, and it is preferable as shown in the drawing to use a pump of the gear type illustrated for example at 43, with which is connected a by-pass safety return passage 44 controlled by a safety check valve 45 yieldingly seated as by a spring 46, of which the tension may be regulated by a suitable plug 47 or the equivalent thereof, so that an excessive pressure which might tend to disarrange or injuriously affect the governor mechanism will be relieved by the opening of the valve 45 and the return of pressure to the feed end 20 of the supply line.

In the modified construction shown in Figure 5, as a means of cutting off the feed of the fuel to the motor in the event of the cessation or reduction of the pressure in the 25 supply line there is employed a cut off valve 41^a adapted to engage the seat 40^a, the stem of said valve having a threaded engagement as at 48 with a bracket 49 which supports the governor mechanism or, obviously, any 30 other suitable stationary or fixed object.

The variation of the resistance offered by the movable element 25^a of the pressure actuable means, and the resistance offered by the spring 20^a to the feeding movement of the needle valve, are regulable by the adjustment of the supply tube 23^a in the seat 50 formed in the bracket 49 and said tube is held in its adjusted positions by the lock nuts 51.

40 The form of Figure 6 is an exceedingly simple, and durable one. It primarily has, compared with Figure 5, a stationary reservoir and avoids use of a slip joint for the overflow pipe. The reservoir in this form is designated 50 and at its top is closed by a head 51 screw threaded or otherwise permanently or removably attached as desired. A fuel supply pipe 52 leads to the head and is coupled thereto at 53. This pipe supplies 45 the oil or other fuel under pressure being associated with the pump 40^c for instance like the pipes 23 and 23^a. Pipe 52 delivers to an inlet passageway 54 in head 51 and communicates with an expansible bellows 55 similar to that at 25^a. The fuel leaves the bellows through the passageway 54 and an L-shaped passageway 56 which leads to the interior of reservoir 50. The extent of opening of the by-pass passageway 56 is 50 governed by the adjustment of a needle valve 57 screw threaded for instance at 58 in the head 51. A manipulating head 59 is provided on the screw 57 and is peripherally milled so as to coact with a spring finger 60 carried by head 51 in order to maintain the

valve in adjusted position against danger of accidental displacement.

Reservoir 50 has a discharge tube 61 and an overflow tube 62 leading to the source of fuel supply or otherwise as preferred. The tube 61 is press-fitted into a block or casing 62 as at 63 and a passageway 64 is provided in said block 62 in continuation of the bore of tube 61. Passageway 64 has a valve seat at 65 and a constricted outlet 66 communicating with an inclined outlet passageway 67 adapted to be alternately opened and closed through operation of an air intake poppet valve 68, controlling entrance of the fuel to a fuel cap 69 and from the same through orifices 70 to the engine cylinder 71. Valve 68 is normally maintained lifted or seated by a spring 72 and the valve has a depression head 73.

80 A needle valve 74 is vertically slidable in the passageway 64 and bore of tube 61 and through a bracket 75 rigidly fastened within the reservoir 50 and having ports or passageways 76 communicating with the bore of tube 61 and the interior of said reservoir. Valve 74 is normally maintained raised with respect to the seat 65 by a spring 77 engaging a cap plate 78 fastened thereon by a nut 79 which is operable along the valve to vary the tension of spring 77. Said rod 74 engages the lower end of the bellows 55 and such end may be in the form of a brass or other plate 80. The point or valve end of rod 74 is shaped similar to the valves 11 and 11^a so as to be incapable of completely closing the seat 65.

85 In operation, the fuel in this form enters through pipe 52 into the bellows 55 and overflows through the passageway 54 and by pass 56, under control of valve 57, into the reservoir and thence through the ports 76 into tubes 61, passageway 64, through valve seat 65, passageway 66, passageway 67, the seat of valve 68, the cup 69 and orifices 70. The flow however is subject to the pressure of the fuel which is imparted to the bellows 55 and expands the same and the action of such bellows is imparted to the valve 74 which correspondingly moves relative to its seat 65 and accomplishes the same result as the devices of the previous forms.

It is to be emphasized that the reservoir 50 in this form is stationary and that the overflow pipe 62 is also stationary, thus leaving the valve 74 as the principal sliding part.

Having thus described the invention, what I claim is:

1. A fuel feed and governor mechanism for motors having a gravity fed needle valve casing, a reservoir for supplying the needle valve port, fuel supplying means for the reservoir, pressure actuable means having a movable element connected with the needle valve and exposed to the variable en-

- gine-load pressure of the fuel in said fuel supplying means, and a by-pass connection between the said pressure actuable means and the reservoir.
5. 2. A fuel feed and governor mechanism for motors having a gravity fed needle valve casing, reservoir for supplying the needle valve port, fuel supplying means for the reservoir, a pressure actuable means having a movable element connected with the needle valve and exposed to the variable engine-load pressure of the fuel in said fuel supplying means, and a by-pass connection between the said pressure actuable means and the reservoir, the reservoir having an overflow outlet to the source of supply.
10. 3. A fuel feed and governor mechanism for motors having a gravity fed needle valve casing, a reservoir for supplying the needle valve port, fuel supplying means for the reservoir, pressure actuable means having a movable element connected with the needle valve and exposed to the variable engine-load pressure of the fuel in said fuel supplying means, and a by-pass connection between the said pressure actuable means and the reservoir, the by-pass having a regulating valve.
15. 4. A fuel feed and governor mechanism for motors having a gravity fed needle valve casing, a reservoir for supplying the needle valve port, fuel supplying means for the reservoir, pressure actuable means having a movable element connected with the needle valve and exposed to the variable engine-load pressure of the fuel in said fuel supplying means, and a by-pass connection between the said pressure actuable means and the reservoir, a cut-off valve actuable upon reduction of the supply pressure being interposed between the reservoir and the needle valve.
20. 5. A fuel feed and governor mechanism for motors having a gravity fed needle valve casing, a reservoir for supplying the needle valve port, fuel supplying means for the reservoir, pressure actuable means having a movable element connected with the needle valve and exposed to the variable engine-load pressure of the fuel in said fuel supplying means, and a by-pass connection between the said pressure actuable means and the reservoir, and means to adjust the relative positions of the needle valve and the movable element of the pressure actuable feed.
25. 6. A fuel feed and governor mechanism for motors having a gravity fed needle valve casing, a reservoir for supplying the needle valve ports, fuel supplying means for the reservoir, pressure actuable means having a movable element connected with the needle valve and exposed to the variable engine-load pressure of the fuel in said fuel supplying means, and a by-pass connection between the said pressure actuable means and the reservoir, the needle valve being yieldingly impelled to open position and means for adjusting the tension of said last named means.
70. 7. A fuel feed and governor mechanism for motors having a gravity fed needle valve casing, a reservoir for supplying the needle valve port, fuel supplying means for the reservoir, pressure actuable means having a movable element connected with the needle valve and exposed to the variable engine-load pressure of the fuel in said fuel supplying means, and a by-pass connection between the said pressure actuable means and the reservoir, and means for varying the resistance offered to pressure by the movable element of the pressure actuable means.
75. 8. A fuel feed mechanism for motors including a reservoir to contain a quantity of fuel for gravity feed to the motor, in combination with a fuel supply passage in communication with the reservoir, and means operable by a replenishing supply of fuel flowing through said passage to control the feed from said quantity to the motor.
80. 9. A fuel feed mechanism for motors including a reservoir to contain a quantity of fuel for gravity feed to the motor, in combination with a fuel supply passage in communication with the reservoir, and means operable by the pressure of a replenishing supply of fuel flowing through said passage to control the feed from said quantity to the motor.
85. 10. A fuel feed mechanism for motors including a fuel line, a reservoir interrupting the fuel line so that the fuel adjacent the discharge portion thereof may flow by gravity to the motor, and means associated with said reservoir operable subject to the pressure in the fuel line to control the flow of the fuel by gravity to the motor.
90. 11. A fuel feed mechanism for motors having fuel-receiving means and a fuel supply passage in communication therewith, a valve to control the feed of fuel from the fuel-receiving means to the motor and means subject to the pressure of fuel in said passage to operate said valve.
95. 12. A fuel feed mechanism for motors having means to supply fuel by gravity to the motor and a fuel supply passage in communication therewith, a valve controlling said first means, and means subject to the pressure of fuel in said passage to vary the extent of opening of the valve.
100. 13. A fuel feed mechanism for motors including a fuel line and a fuel supply passage in communication therewith, a reservoir interrupting the fuel line so that the fuel adjacent the discharge portion thereof may flow by gravity to the motor, and means
105. 110. 115. 120. 125. 130.

operable through the flow of fuel through said passage to control the flow of the fuel by gravity to the motor incapable of completely cutting off the flow of fuel to the 5 motor during operation of the latter.

14. A fuel feed mechanism for motors including a fuel line and a fuel supply passage in communication therewith, a reservoir interrupting the fuel line so that the 10 fuel adjacent the discharge portion thereof may flow by gravity to the motor, and means operable through the flow of fuel through said passage to control the flow of the fuel by gravity to the motor consisting 15 of a valve imperfectly seated whereby it will be incapable of completely cutting off the supply of fuel to the motor during operation of the latter.

15. A fuel feed mechanism for motors, in 20 combination with a fuel supply passage, having means expandible and contractile according to the pressure of the fuel flowing in said passage, and valve means to control the flow of the fuel between the first 25 means and the motor operable by the first mentioned means.

16. A fuel feed mechanism for motors, in 30 combination with a fuel supply passage having means expandible and contractile according to the pressure of the fuel flowing 35 in said passage, valve means to control the flow of the fuel between the first mentioned means and the motor operable by the first mentioned means being in contact therewith and means to urge the valve means toward the first mentioned means.

17. A fuel feed mechanism for motors having a fuel reservoir from which the fuel flows to the motor, means in the reservoir 40 subject to the pressure of the fuel, means forming a passage from the first mentioned means into the reservoir, and a valve controlling the outlet of fuel from the reservoir to the motor under control of the first 45 mentioned means.

18. A fuel feed mechanism including a block, a reservoir in communication with the block, said block having a passageway therethrough in communication with said reservoir, a valve in said passageway, an element within the reservoir expandible and contractile according to the pressure of the fuel and being in contact with said valve, a spring to urge said valve toward said element, and said reservoir having a passage communicating with its interior, with said element and with the source of supply, a regulating valve for said passage, and an air intake valve in said block normally closing the passageway. 60

19. A fuel feed mechanism having a block, a fuel cup carried thereby and in communication with the cylinder of an engine, an air intake valve carried by the block, said block having a fuel supply passageway therethrough normally closed by said valve, a stationary reservoir having a depending tube press fitted into the block, said tube having a passageway communicating with the passageway of the block, 70 a bracket within the reservoir in communication with said passageway, a needle valve slidably disposed in said passageway and in said bracket, a detachable head on said reservoir, and expansive and contractile elements subject to the pressure of the fuel depending from said head and contacting with said needle valve, a nut threaded on said needle valve, an expansive spring surrounding said bracket, a plate on the needle valve in abutment with said springs and positioned by said nuts, said head having an inlet passageway leading from the source of fuel supply to said elements, said head having a by-pass leading from said inlet 75 passageway to the interior of the reservoir, and a control valve for said by-pass adjustably mounted in said head.

In testimony whereof I affix my signature.
GEORGE C. WRIGHT.
